TOY SAILBOAT WITH STEERING MEANS

Robert S. Wentworth, Mamaroneck, N. Y.

Application October 26, 1946, Serial No. 706,833

11 Claims. (Cl. 46—83)

This invention relates to sailboats and aims to provide an improved toy sailboat. The sailing of toy sailboats entails loss of control of the boat by the sailor after the boat is under way. In the past, this has hampered toy-boat sailing. It has been necessary to sail the boats along a fixed course and after the boats are under way that course cannot be changed. As a consequence, the use of toy sailboats has been limited to small ponds or bays so that the course selected would end at a point along a shore opposite the point from which the boat was launched. When this not not done, it was most difficult to recover the boat.

I have discovered that an ordinary toy sailboat can be equipped with inexpensive apparatus which will cause it to turn around automatically after it has sailed for a predetermined time and then return to the same or nearly the same point from which it was launched.

A sailboat constructed in accordance with my invention has, in addition to the conventional boom, a rudder and tiller, and a sheet connecting the tiller with the boom. Movable members or stops are provided to limit the movement of the tiller under the pull of the sheet on each tack so as to hold the tiller in the position required to cause the boat to sail along a predetermined course. The boat also has timed means for automatically withdrawing the stop 30 against which the tiller is urged by the sheet to permit the pull of the sail to turn the tiller and rudder, so that the boat turns around after a predetermined time. The other stop then holds the tiller against the pull of the sheet so that 35 the boat sails back to the shore from which it has sailed.

In order that my invention will be clearly understood, I will describe the specific embodiment of it which I now prefer and which is illustrated in the accompanying drawings in which:

Fig. 1 is a side elevation of a sailboat incorporating my invention and arranged to jibe after it has sailed for a predetermined time;

Fig. 2 is a plan view of the boat illustrated in Fig. 1 with the sails removed;

Fig. 3 is a view similar to Fig. 2 of a boat arranged to come about into the wind after it has sailed for a predetermined time;

Fig. 4 is a sectional elevation of the timing mechanism;

Fig. 5 is a rear elevation of the timing mechanism illustrated in Fig. 4; and

Fig. 6 is a sectional elevation of a modified type of timing mechanism.

2 The sailboat illustrated in the drawings is a sloop having a conventional hull 8, mast 9 and boom 10. An ordinary jib 11 and mainsail 12 are supported by the mast 9. A rudder 14 is connected with a parallel tiller 15 through a rudder post 16. The rudder 14 is preferably balanced as illustrated in Fig. 1 by attaching it to the rudder post 16 midway between its ends, for such a rudder will not change position when no external force is applied to the tiller.

15 The tiller 15 is elongated so that its ends extend fore and aft of the rudder post 16 to which it is connected. The main sheet 18 connects the boom 10 with an end of the tiller 15 instead of the usual cleat fastened to the deck, so that the pull of the mainsail 12 tends to turn the rudder 14. Movable members 20, 20' normally hold the tiller in fore and aft position.

20 The members 20, 20' are L-shaped and are pivoted to the deck 19 at 22, 22' respectively. Arms 23, 23' extend upwardly from those members so that they are adapted to engage the port and starboard sides respectively of the tiller 15 near one end.

25 Either arm 23 or arm 23' can be swung outside of the path of the tiller 15 by the piston 25 in cylinder 26. The cylinder 26 has ears 27 which are fastened to the deck 19. The piston 25 is connected through an arm 28 with a link 29 having a hook 31 at its end. The hook 31 is adapted to fit into the slots 33 or 33' of the arms 23, 23'. The L-shaped members 20, 20' bear against the stops 34, 34' fixed to the deck 19 when they hold the tiller 15 in fore and aft position, and when the L-shaped members are in this position it is necessary that the piston be at the end of its stroke to permit the hook 31 to be inserted in slot 33 or 33'. Then, during the out-stroke of the piston, the arm 23 or 23' with which the link 29 is connected is slowly pulled away from the path of the tiller 15.

26 The piston 25 is moved away from the head of the cylinder 26 by a spring. In the mechanism illustrated in Fig. 4, a compression spring 36 contained within the cylinder performs this function. In the modification illustrated in Fig. 6, the piston 25 is pulled away from the head of the cylinder 26 by means of a tension spring 37 anchored to the deck 19 through arm 28.

27 The rate of travel of the piston 25 during its outstroke is governed by a needle valve 38 which controls the rate at which air is admitted to the cylinder 26 through port 41. The head 42 of needle valve 38 is preferably calibrated as illus-

trated in Fig. 5 to indicate the rate of travel of the piston 25 during its out-stroke.

The operation of my sailboat is as follows: The main sheet 18 is payed out sufficiently to permit the boom 16 to swing to the position desired for the course selected. I prefer to connect the main sheet to the after end of the tiller 15 as illustrated in Fig. 2 so that the boat will jibe when the arm 23 is swung away from the path of the tiller. This causes the boat to reverse its direction quickly so that it will not lose headway in a light breeze. The members 20, 20' are pushed against the stops 34, 34' and the hook 30 is inserted in the slot 33 or 33' of windward arm 23 or 23'. The boat is then launched upon its course and the piston 25 slowly swings the arm 23 or 23' with which it is connected away from the path of the tiller 15. The pull of the sail 12 then swings the forward end of the tiller to windward and the boat jibes. After the boat has jibed, the pull of the sail swings the tiller back to fore and aft position and holds it in that position against the arm 23 or 23' which is to windward after the direction of the boat has been reversed. The boat then sails back to the place from which it was launched.

Under some circumstances, it is preferable to bring the boat about into the wind to reverse its direction. This is accomplished by attaching the main sheet 18 to the forward end of the tiller and the piston 25 is connected with the arm 23 or 23' which is to leeward when the boat is first set on its course (Fig. 3). After that arm has been moved out of the way of the tiller and the boat has come about, the other arm holds the tiller in fore and aft position so that the boat returns to the place from which it was started.

A particularly intriguing feature of my boat is that the behavior of the boat under sail is usually dependent to a large degree upon the judgment and skill of the sailor. Under constant conditions of a steady breeze and no current, the boat will reverse the course chosen for it so that it will return to the place from which it was launched. However, with a variable breeze and with a current, skill is required to sail the boat so that it will return to a selected place. Furthermore, my boat can be caused to follow a set course and round a marker closely at the end of that course under skillful handling.

It will be appreciated that the practice of my invention is not limited to toy sloops but it may be incorporated in any toy sailboat with fore and aft rigging, and it will be apparent to those skilled in the art that other modifications may be made in the specific embodiment which I have described without departing from my invention.

What I claim is:

1. A sailboat having a boom, a rudder, a tiller, a sheet extending from the boom to the tiller, a pair of opposed separately movable stop members adapted to hold the tiller in fore and aft position, automatic means operable selectively to move only one of said members so that the tiller can be swung to one side, and means for timing the operation of said automatic means.

2. A sailboat having a boom, a rudder, a tiller, a sheet extending from the boom to the tiller, a pair of opposed separately movable stop members adapted to hold the tiller in fore and aft position, and automatic means operable after a predetermined interval selectively to move only one of said members so that the tiller can be swung to one side.

3. A sailboat having a mast, a mainsail, a main

boom attached to the mast for pivotal movement, a rudder, a tiller, a pair of opposed separately movable members adapted to hold the tiller in fore and aft position, a sheet connecting the boom with the rudder so that movement of the boom beyond a predetermined angle will turn the rudder and tiller, and automatic means operable after a predetermined interval selectively to move only one of said members so that the rudder can be swung to one side by the pull of the sail.

4. A sailboat having a mast, a mainsail, a boom, a rudder, a rudder post, a tiller attached to the rudder post so that each of its ends extends beyond said rudder post, movable members adapted to hold the tiller in fore and aft position, automatic means operable after a predetermined interval to move one of said members, and a sheet adapted to connect the boom with either of said ends of the tiller.

5. A sailboat having a mast, a mainsail, a boom, a rudder, a tiller, a pair of opposed separately movable members adapted to hold the tiller in fore and aft position, automatic means operable after a predetermined interval selectively to move only one of said members, and a sheet connecting the boom with the tiller so that on the movement of said member the pull of the sail will turn the tiller and rudder to cause the boat to jibe.

6. A sailboat having a mast, a mainsail, a boom, a rudder, a tiller, a pair of movable members adapted to hold the tiller in fore and aft position, automatic means operable after a predetermined interval to move one of said members, and a sheet connecting the boom with the tiller so that on the movement of said member the pull of the sail will turn the tiller and rudder to cause the boat to come about.

7. A sailboat having a boom, a balanced rudder, a tiller, a sheet extending from the boom to the tiller, a pair of opposed separately movable stop members adapted to hold the tiller in fore and aft position, and automatic means operable after a predetermined interval selectively to move only one of said members so that the tiller can be swung to one side.

8. A sailboat having a boom, a rudder, a tiller, a sheet extending from the boom to the tiller, a pair of L-shaped members pivoted to opposite sides of the deck of the boat and each having an arm adapted to engage one side of said tiller when it is in fore and aft position, and automatic means operable after a predetermined interval to pivot either of said members so that its arm is swung to a position outside of the path of the tiller.

9. A sailboat having a boom, a rudder, a sheet connecting the boom with the tiller, a tiller, a pair of movable members adapted to hold the tiller in fore and aft position, a cylinder, a piston, means for connecting either of said movable members with the piston at the end of its in-stroke, means for urging the piston outwardly so that the movable member to which it is connected is withdrawn from the path traversed by the tiller upon turning of the rudder in one direction, and means for timing the outward movement of said piston.

10. A toy sailboat having a boom, a rudder, a tiller, a sheet connecting the boom with the tiller, a pair of movable members adapted to hold the tiller in fore and aft position, a cylinder having a port near its head, a piston in said cylinder, means for connecting either of said movable members with the piston at the end

of its in-stroke, a spring connected with the piston and adapted to force the piston outwardly so that the movable member to which the piston is connected is withdrawn from the path traversed by the tiller upon turning of the rudder in one direction, and a needle valve adapted to control the admission of air into the cylinder through said port.

11. The combination with a toy sailboat having its main sheet attached to its tiller, of a pair of opposed separately movable stops positioned to limit the turning movement of the tiller under the pull of the sheet in each direction, and timed means for selectively withdrawing either one of said stops.
